UNITED STATES PATENT OFFICE.

JOHN F. O'CONNOR, OF CHICAGO, ILLINOIS, ASSIGNOR TO WILLIAM H. MINER, OF CRAZY, NEW YORK.

FRICITION SHOCK-ABSORBING MECHANISM.

Application filed May 5, 1921. Serial No. 466,913.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a high capacity shock absorbing mechanism especially adapted for railway draft riggings and wherein are obtained certain release, a graduated smooth action, long life, uniform action at all times, low stresses on all friction elements, and low ultimate or peak load transmitted to the car underframe or other supporting framework.

Another object of the invention is to provide a mechanism of the character indicated in the preceding wherein are employed duplicated wedging or pressure-creating systems cooperable with a single group of intercalated friction elements.

Another object of the invention is to provide a mechanism having duplicated wedging or pressure-creating systems in which each of the systems consists of a plurality of wedging elements having anti-friction means therebetween and wherein also anti-friction means are employed between each of the systems and the group of intercalated friction elements to the end that the mechanism is unusually sensitive both in setting up the desired pressure on the friction elements during compression and in releasing or reducing said pressure instantaneously upon removal of the actuating force and at the initiation of the release stroke.

Other objects of the invention will more clearly appear from the description herein-after following.

In the drawings forming a part of this specification, Figure 1 is a longitudinal, horizontal, sectional view of a portion of a railway draft rigging showing my improvements in connection therewith. Figure 2 is a vertical, transverse, sectional view corresponding substantially to the line 2--2 of Figure 1. Figure 3 is an enlarged transverse, sectional view of the shock absorbing

mechanism proper and corresponding substantially to the line 3--3 of Figure 1. Figure 4 is a broken, longitudinal, vertical, sectional view corresponding substantially to the section line 4--4 of Figure 3. Figures 60 5 and 6 are detail perspectives of the spring follower and one of the floating wedge elements, respectively, employed in the mechanism. And Figure 7 is a perspective of two of the so-called stationary friction 68 plates illustrating more particularly the manner of accommodating the retainer bolts of the mechanism.

In said drawings, 10--10 denote channel draft sills of a railway car, to the inner faces 70 of which are secured front stop lugs 11 and rear stop lugs 12, which may be of any desired form. The rear portion of a drawbar is indicated at 13, the same being operatively associated with the shock absorbing mechanism proper by means of a hooded cast yoke 14 and coupler key 15. The yoke and parts within are supported in operative position by a detachable saddle plate 16.

The improved shock absorbing mechanism 80 proper, as shown, comprises, broadly, a column-load-sustaining member A; twin springs B--B; a spring follower C; a series of relatively stationary friction elements D--D; a series of relatively movable friction elements E--E; a front follower F; floating wedge elements G--G; anti-friction rollers H--H; anti-friction rollers J--J; and retainer bolts K--K.

The load-sustaining member A, the details 90 of which obviously may vary without departing from the spirit of the invention, is preferably in the form of a malleable casting having top and bottom horizontal walls 17--17, an integral rear connecting vertical 95 wall 18 operating as a follower in conjunction with the stop lugs 12, and vertical side walls 19--19 at the front or outer end of the casting. Said side walls 19--19 are relatively short in a direction parallel to the 100 axis of the mechanism in order to leave the greater portion of the sides of the member A open to permit of the introduction and removal of the spring follower C and twin springs B. With the arrangement shown, 105 it is evident that the forward end of the member A constitutes, in effect, a hollow substantially rectangular box or casing and that the member A, as an entirety, is adapted to act as a column in the transmission of 110

the shocks to the car underframe and also functions as the rear follower of the mechanism.

Within the box-like casing portion of the member A, above referred to, and centrally thereof, are provided upper and lower recesses 20-20. The forward flanges formed in the member A because of the recesses 20-20 are notched in vertical alinement as indicated at 21-21 and in the center line of the mechanism as indicated in Figure 2, the width of said notches 21 being slightly greater than the thickness of the top and bottom edges of the stationary friction plates D, for the purpose hereinafter described. Within said recesses 20, in addition to the front set of transversely extending flanges 22-22, as shown in Figure 4, are formed other transversely extending sets of vertically alined shoulders or ribs 23 and 24, said ribs 23 and 24 providing forwardly facing shoulders, whereas the flanges 22 provide rearwardly facing shoulders. Said three sets of vertically alined shoulders 22, 23 and 24 cooperate respectively with the forwardly facing shoulders 122 and rearwardly facing shoulders 123 and 124 on said stationary friction plates D. With this construction it is evident that the plates D may be inserted longitudinally within the casing portion of the member A one at a time through the central notches 21 and then shifted laterally to either side of the center line to the positions best shown in Figure 3 and when so positioned, said plates D are held against longitudinal movement with respect to the member A but are sensitive to laterally exerted pressure thereon.

Each of the said plates D preferably has a channel-like groove 25 extending lengthwise thereof, thus leaving the top and bottom edges of the plates considerably thicker than the central portions thereof. The movable plates E which are alternated with the plates D are of slightly less width than the width of the channels 25 and of a thickness slightly greater than the depth of the channels 25 so that, when the stationary and movable plates are properly assembled as shown in Figure 3, a slight clearance as indicated at 26 is left between the thick edges of the plates D so as to leave all plates sensitive to lateral pressure and also allow for a certain amount of wear of the rubbing faces of the plates. In actual practice, I prefer to employ six of the plates D, three of the same having their channels faced toward the left and three with their channels faced toward the right, as viewed in Figure 3 so that the two central plates D will be arranged back to back. Said two central plates D are provided with longitudinally extending semi-cylindrical grooves as indicated at 27 in their top and bottom edges 65 so when said two plates are assembled back

to back, they provide longitudinally extending openings to accommodate the retainer bolts K. Said retainer bolts K are anchored at their rear ends in suitable pockets formed in the member A and at their forward ends 70 in suitable recesses provided therefor in the front follower F. As will be understood by those skilled in the art, the bolts K maintain all of the parts in assembled relation and also may be utilized to place the spring 75 resistance under an initial compression.

The movable plates E are preferably rectangular in outline with flat surfaces on both sides so that the same may be cheaply manufactured from rolled steel strips. The 80 plates E are longer than the plates D and extend outwardly from the member A, the inner ends of said plates E also preferably normally extending slightly inwardly beyond the inner edges of the plates D, as 85 shown in Figure 1. As indicated in the preceding, the plates E are intercalated and preferably alternated with respect to the plates D so that, upon longitudinal movement of the plates E, friction is generated 90 between all of said plates E and all of the plates D.

The front follower F is preferably in the form of a malleable casting and has laterally spaced inwardly extended heavy pressure-transmitting flanges 28-28 which straddle the plates E and provide a pocket within which the outer ends of the plates E are accommodated. To avoid bending of the ends of the plates E and gouging of the 100 follower F when the latter actuates the plates E, a loose hardened wear plate 29 may be interposed between said plates E and the follower F. The thickness of the wear plates is less than the normal space 105 between the outer ends of the movable friction plates and the follower F and may, therefore, assume either a spaced position relatively to said follower, or relatively to the outer ends of said plates. In the normal condition of the parts, assuming that the plate is in the position abutting the outer ends of the friction plates, as shown in Fig. 1, a small space as indicated at 110 30 is left between the follower F and the plate 115 29, said space preferably approximating about half an inch so that, during the first half inch movement of the follower F, during a buffing action, the plates E will not be actuated.

As clearly shown in the drawing, the spring resistance embodies twin springs B of the desired length, capacity and movement. The forward ends of said springs engage the rear face of the spring follower C. 125 The forward flat transversely extending face 31 of said follower C normally engages the inner ends of the movable plates E as shown in Figure 1. On each side, the follower C is provided with an elongated forwardly ex- 130

tended arm 32 and each of said arms 32, at a point substantially centrally thereof, is provided on its inner side with a wedge roll seat 33, against which bears the corresponding anti-friction roller H. A suitable shoulder 34 is also formed at the end of the wedge roll seat 33, in order to maintain the rollers H in proper position. The forward or extreme ends of the arms 32 telescope within recesses 36 formed near the side edges of the follower F.

Two floating wedge elements G are employed, the same being of like construction. Each of said elements G is formed on its outer side with a wedge roll seat 36 parallel to the corresponding adjacent roll seat 33. A suitable roller stop shoulder 37 is also formed on each element G adjacent the roll seat 36 to assist in maintaining the anti-friction rollers H in proper position. At their outer or forward ends, the elements G are formed with transversely extending flat bearing surfaces 38 which are engaged by the inner ends of the pressure-transmitting flanges 28 of the follower F. On its inner side, which extends parallel to the center line of the mechanism, each element G is provided with a pair of recesses 39-39 which accommodate the anti-friction rollers J. The depth of said recesses 39 is less than the diameter of the rollers J so that the latter extend outwardly beyond the surface of the element G and thus are adapted to roll freely on the respective adjacent movable friction plate E. The width of said recesses 39 is also left great enough to admit of a free rolling movement of the rollers J.

As will be evident from an inspection of Figure 1, the outer faces of the arms 32 of the spring follower C are preferably slightly spaced from the opposed inner faces of the walls of the member A so that friction between said follower C and the member A is avoided.

The operation of the device is as follows, assuming an inward or buffing movement of the drawbar. As the drawbar 13 is forced inwardly, the front follower F is moved simultaneously and uniformly therewith, it being understood that the column-load-sustaining member A is held stationary by the rear stop lugs 12. For the first approximate half inch inward movement of the follower F, no movement of the plates E occurs, as hereinbefore described but the floating wedge elements J are moved inwardly in unison with the follower F. This movement is resisted by the spring resistance reacting through the spring follower C and the wedge elements formed rigidly thereon. Hence during the initial approximate half inch movement of the follower F, lateral pressure is created oppositely and inwardly against the outer sides of the centrally disposed group of intercalated friction plates before

any relative movement of said plates takes place. Obviously, this wedging action or pressure-creating action set up is determined by the spring resistance and the action is extremely sensitive because of the anti-frictional mounting between the respective sets of wedge elements and the anti-frictional means interposed between the floating elements G and the friction plates. During the initial action just described, it is evident that the spring follower C will be moved rearwardly so as to be disengaged from the inner ends of the plates E. As the follower F continues its inward movement, it will then actuate the movable plates E inwardly simultaneously therewith and this action continues until the follower F is limited in its movement relatively toward the member A by engaging the forward edges of the latter. Upon removal or discontinuance of the actuating force, the pressure from the follower F upon the floating wedge elements G is of course relieved and the springs B are then free to force the follower E outwardly. Due to the anti-frictional means between the wedge elements of each system and between the system and the friction elements, said elements are free to move relatively to each other and also free to move relatively to the friction elements and the wedging action is thus immediately reduced and the parts forced outwardly by the spring follower C without any relative movement of the friction plates E and D. This initial portion of the release action continues until the follower C engages the inner ends of the plates E at which time the pressure between the intercalated plates has been reduced to a minimum and the follower C, under the expansion of the spring resistance, may easily project the plates E outwardly toward their normal full release position.

From the preceding description, it will be seen that the maximum stresses set up in any of the elements is dependent upon the ultimate capacity of the spring resistance and is independent of the strength of the applied actuating force. Consequently, the entire device is free from any excessive stresses and the pressure on the cooperating friction elements is maintained at a relatively low figure per unit of area, thereby minimizing wear and promoting long life for the mechanism. The low pressure per unit of area on the frictional surfaces is however, fully compensated because of the large number and area of friction generating surfaces, the area being several times that now employed in commercial types of friction gears most commonly used by the railroads.

I have herein shown and described what I now consider the preferred manner of carrying out the invention but the same is merely illustrative and I contemplate all

changes and modifications that come within the scope of the claims appended hereto.

I claim:

1. In a friction shock absorbing mechanism; the combination with a column-load-sustaining member; of a group of intercalated relatively longitudinally movable and stationary friction elements mounted on said member; of an outer follower; a spring resistance; a follower interposed between said spring resistance and said group of friction elements, one of said followers having spaced wedge elements rigid therewith and located at opposite sides of said groups of friction elements; and additional wedge elements interposed between said first named wedge elements and the group of friction elements adapted to augment the lateral pressure between said elements upon relative movement of said outer follower and member toward each other.
2. In a friction shock absorbing mechanism, the combination with a column-load-sustaining member; of a group of intercalated relatively longitudinally movable and stationary friction elements mounted on said member; of a spring resistance; a follower interposed between said spring resistance and said group of friction elements, said follower having spaced wedge elements rigid therewith and located at opposite sides of said groups of friction elements; an outer follower; additional wedge elements interposed between said first named wedge elements and the group of friction elements adapted to augment the lateral pressure between said elements upon relative movement of said outer follower and member toward each other; anti-friction means interposed between said additional wedge elements and the respective first named wedge-elements; and anti-friction means interposed between said additional wedge elements and the group of friction elements.
3. In a friction shock absorbing mechanism, the combination with a column-load-sustaining member; of a series of friction elements carried by said member and held against longitudinal movement with respect thereto; an outer follower; a series of relatively movable friction elements intercalated with respect to the friction elements of the first series and movable longitudinally relatively to said member, said intercalated elements being so disposed as to form a single group, and said movable friction elements being adapted to be actuated by said follower upon relative approach of said follower and member; a spring resistance; a spring follower; and lateral-pressure-creating means cooperable with said intercalated friction elements including, a wedge element rigid with respect to said spring follower and located at one side of said friction elements and a floating wedge element

interposed between said first named wedge element and the friction elements, said floating wedge element being directly actuated by said outer follower.

4. In a friction shock absorbing mechanism, the combination with a column-load-sustaining member; of a series of friction elements carried by said member and held against longitudinal movement with respect thereto; an outer follower; a series of relatively movable friction elements intercalated with respect to the friction elements of the first series and movable longitudinally relatively to said member, said intercalated plates being so disposed as to constitute a single centrally disposed group, said movable friction elements being adapted to be actuated by said follower upon relative approach of said follower and member; a spring resistance; a spring follower; lateral-pressure-creating means cooperable with said intercalated friction elements including, spaced wedge elements rigid with respect to one of said followers and located at opposite sides of said groups of friction elements and floating wedge elements interposed between said first named wedge elements and the friction elements, said floating wedge elements being directly actuated by said outer follower; anti-friction means interposed between said wedge elements; and anti-friction means interposed between the floating wedge element and the friction elements.

5. In a friction shock absorbing mechanism, the combination with a column-load-sustaining member adapted to function as a follower; of a series of friction plates carried by said member and held against movement longitudinally with respect thereto; of an outer main follower; a series of relatively movable friction plates intercalated with respect to the first named friction plates and movable relatively longitudinally of said member, said movable friction plates being normally slightly spaced from said main follower and adapted to be actuated by the latter during relative approach of said follower and member, said intercalated friction plates being so disposed as to constitute a single centrally disposed group; a spring resistance; a spring follower interposed between said resistance and the group of friction plates; and a lateral-pressure-creating system on each side of the group of friction plates, each system including, a wedge element rigid with respect to said spring follower and a floating wedge element interposed between said first named wedge element and the adjacent side friction plate, said floating wedge elements being directly actuated by said outer main follower.

6. In a friction shock absorbing mechanism, the combination with a hollow casting having a rectangular open-ended casing at

one end thereof, a follower at the other end thereof and a spring cage therebetween; of a spring resistance disposed within said cage; a series of relatively stationary friction plates mounted within said casing portion and held against movement longitudinally relatively thereto; a series of relatively movable friction plates alternated with said stationary friction plates and having their outer ends projecting outwardly from said member, the two series of plates constituting a single central group and the inner ends of said movable plates projecting inwardly of the stationary plates; a spring follower 10 within said member and engaging the spring resistance on one side and said inner ends of the movable plates on the other side, said spring follower being provided on each side thereof with a forwardly extended wedge section, the wedge sections straddling the group of friction plates; an outer main follower; and floating wedge elements on each side of the group of friction plates, each floating wedge element cooperating with the corresponding adjacent spring follower wedge element, said floating wedge elements being directly actuated by engagement with the abutment member on said main follower; anti-friction rollers interposed between each set of wedge elements; and anti-friction rollers interposed between each floating wedge element and the group of friction plates. 65

8. In a friction shock absorbing mechanism, the combination with a hollow casting having a rectangular open-ended casing at one end thereof, a follower at the other end thereof and a spring cage therebetween; of a spring resistance disposed within said cage; a series of relatively stationary friction plates mounted within said casing portion and held against movement longitudinally relatively thereto; a series of relatively 70 movable friction plates alternated with said stationary friction plates and having their outer ends projecting outwardly from said member, the two series of plates constituting a single central group and the inner ends of said movable plates projecting inwardly of the stationary plates; a spring follower within said member and engaging the spring resistance on one side and said inner ends of the movable plates on the other side, 75 said spring follower being provided on each side thereof with a forwardly extended wedge section, the wedge sections straddling the group of friction plates; an outer main follower, said follower being recessed to accommodate the outer ends of said movable friction plates and wedge sections; and floating wedge elements on each side of the group of friction plates, each floating wedge element co-operating with the corresponding 80 adjacent spring follower wedge element, said floating wedge elements being directly actuated by the inner face of said inner recessed portion of said main follower, said main follower being normally slightly spaced from the outwardly projected ends of the movable friction plates. 85

9. In witness that I claim the foregoing I have hereunto subscribed my name this 22nd day of Apr. 1921.

JOHN F. O'CONNOR.
